GEORGE H. JOHNSON, OF BUFFALO, NEW YORK, ASSIGNOR TO HIMSELF AND GEORGE W. TIFFT, SONS, AND COMPANY, OF SAME PLACE.

Letters Patent No. 86,926, dated February 16, 1869.

IMPROVED ELEVATOR-LEG.

The Schedule referred to in these Letters Patent and making part of the same.

To all whom it may concern:

Be it known that I, GEORGE H. JOHNSON, of the city of Buffalo, in the county of Erie, and State of New York, have invented a certain new and useful Improvement in the Construction of Metallic Elevator-Legs; and I do hereby declare that the following is a full and exact description thereof, reference being had to the accompanying drawings, making part of this specification.

My invention relates to what are technically called the indoor legs of an elevator; that is, those employed within the store-houses for distributing the grain to the bins, and discharging it therefrom.

The usually great height of such legs, and the fact that they require to pass up through the grain-bins, present serious difficulties to their construction of metal in position at the elevator.

The object of my improvement is to avoid such difficulties of construction, and the consequent great expense of the structure.

My invention for accomplishing this, consists in constructing the bucket-tubes or leg itself in sections, finished complete at the shop or manufactory, which can be readily connected in forming the leg by simply bolting them together, thereby dispensing with the labor and necessity of riveting the parts under circumstances so impracticable as at the elevator.

In the drawings—

Figure I is a side elevation of my improved elevator-leg.

Figure II is a rear elevation.

Figure III is a view of a fragment of two sections of a bucket-tube, detached.

Figure IV is a view of an adjacent side of the same.

Figure V is a cross-section thereof.

Like letters of reference designate like parts in all of the figures.

A A and A' A' represent the sections, forming respectively the front and rear bucket-tubes of an elevator-leg.

B is the head-box, which connects the upper ends of the tubes A A', and receives the head-pulley, over which passes the belt carrying the buckets.

An extension, B', of this box forms the spout, through which the grain from the buckets is discharged.

C is the foot-box, connecting the lower ends of the bucket-tubes, in which is mounted the foot-pulley of

the elevator-belt. It is provided with the ordinary openings at the bottom and sides, for the passage of the grain to the buckets.

The tube-sections A A' are each formed of sheet-metal plates, D D', the plates D projecting beyond the ends of the adjacent ones D', as shown in Fig. V, and forming a tube rectangular in cross-section.

These plates are secured together by angle-bars, e e', applied longitudinally to the outer angles formed by the projecting portions of the plates D, to which the edges of both plates are riveted. These angle-bars also serve to stiffen the tubes.

F represents a rectangular ring-casting, formed with two flanges, f and f', at right angles to each other.

Each end of the sections D D' has secured to it one of these flanged castings, which is effected by riveting to the flange f' the ends of the plates forming the section.

These sections of the bucket-tubes are finished complete at the shop, and two sections, A A', may be connected by the diagonal braces g g, before they are transported to the elevator.

The sections are readily connected together, in forming the elevator-leg, by bolts, i i, passing through the contiguous flanges f' f' of the abutting sections.

By thus forming the bucket-tubes or elevator-leg in sections, no riveting is required to be done at the elevator, while the construction of the sections at the shop, with the facilities which it affords for heating the rivets, of light, and convenience in riveting the parts together, enable me to construct an elevator at a greatly reduced expense from that otherwise required. This difference in the cost of construction is an important item.

Another advantage and result of my improved construction of an elevator-leg is that of portability, which the leg thus acquires.

Having thus described my invention,

What I claim, and desire to secure by Letters Patent, is—

The iron elevator-leg, constructed in sections, substantially as herein described; as a new article of manufacture.

GEO. H. JOHNSON.
